CLAIM

I claim, the ornamental design for the carriage for infant car seat, as shown and described.

DESCRIPTION

FIG. 1 is a left side view of a carriage for infant car seat showing my new design, handle shown in a lowered position in broken lines;

FIG. 2 is a rear view thereof;

FIG. 3 is a front view thereof;

FIG. 4 is a top view thereof;

FIG. 5 is a bottom view thereof; and,

FIG. 6 is a perspective view thereof.

The broken lines shown in the drawings are included for the purpose of illustrating environment and form no part of the claimed design.
